(57) **CLAIM**

The ornamental design for a detail brush handle, as shown and described.

DESCRIPTION

FIG. 1 is a first, bottom perspective view of a detail brush handle according to the present disclosure;

FIG. 2 is a second, bottom perspective view of the detail brush handle of FIG. 1;

FIG. 3 is a first, top perspective view of the detail brush handle of FIG. 1;

FIG. 4 is a second, top perspective view of the detail brush handle of FIG. 1;

FIG. 5 is a bottom plan view of the detail brush handle of FIG. 1;

FIG. 6 is a top plan view of the detail brush handle of FIG. 1;

FIG. 7 is a front elevation view of the detail brush handle of FIG. 1; and,

FIG. 8 is a side elevation view of the detail brush handle of FIG. 1, the opposite side view being a mirror image thereto.

1 Claim, 7 Drawing Sheets---
